UNITED STATES PATENT OFFICE.

JOHN EDWARD ERCANBRACK, OF CHICAGO, ILLINOIS, ASSIGNOR OF ONE-THIRD TO
GEORGE F. PAUL AND ONE-THIRD TO RALPH N. HARTWICK, BOTH OF CHICAGO,
ILLINOIS.

HEAT-EXCHANGE UNIT.

Application filed August 4, 1923. Serial No. 655,664.

To all whom it may concern:

Be it known that I, JOHN EDWARD ERCANBRACK, a citizen of the United States, and a resident of Chicago, in the county of Cook and State of Illinois, have invented a certain new and useful Improvement in a Heat-Exchange Unit, of which the following is a full, clear, and exact description, such as will enable others skilled in the art 10 to make and use the same.

My invention relates to means for modifying the temperature of fluids and is more particularly directed to tempering of water and air to raise or lower the temperature 15 thereof.

One of the objects of my invention is to provide a heat exchange unit, or similar means, in and through which a fluid such as steam, hot water, or brine may be circulated, 20 and the unit is adapted to be either immersed in a tank of water or positioned within a compartment through which air is circulated.

In tempering air for use in heating with 25 warm air the structure is usually mounted in a chamber that is interposed in the air flue leading from a suitable source of supply, and the steam is circulated in the tubes of the structure, first upon one side 30 and then upon the opposite side of a central, or a box-like compartment or header to which the tubes are connected and with the interior of which said tubes communicate. Further objects of my invention relate 35 side in providing a structure of this character that is comparatively simple in construction and which may be readily assembled or fabricated and placed upon the market as a unit. In constructing the unit 40 I have divided the same into a primary and a secondary side so that the fresh steam or other tempering fluids flowing through the unit may be readily distributed. Also, with a primary and secondary side I am 45 able to better regulate the temperature of the fluid being tempered and change the temperature either suddenly or gradually as may be found most desirable or necessary in the particular case. In this connection I 50 provide a unit in which the cylinders and tubes, and other elements, are free to ex-

pand or contract without strain to the structure which prevents distortion of the parts. This is quite essential as it will permit, at any time, of the disassembly of any one or 55 more of the cylinders and tubes without interference with remaining elements.

I prefer to carry out my invention in substantially the manner hereinafter described and as more particularly pointed out in the 60 claims, reference being had to the accompanying drawings that form a part of this specification.

In the drawings:

Figure 1 represents a vertical side elevation of my heat exchange unit.

Fig. 2 is an end view of the structure illustrated in Figure 1.

Fig. 3 is a transverse section drawn to an enlarged scale and taken on line 3-3 of 70 Figure 1.

Fig. 4 is a top plan of my improved unit showing the same installed in a structure for heating or tempering air.

Fig. 5 is a top plan showing an installation for heating water in a tank.

Fig. 6 is a vertical sectional view showing the use of my heat exchange unit with brine for the purpose of cooling water or air.

In the drawings so far as practicable the 80 same reference characters have been employed to designate like parts wherever they occur, and by referring to Figures 1, 2, and 3 it will be observed my invention preferably comprises a casing or header consisting of exterior side walls 10 of substantially rectangular outline and spaced apart in parallel relation, which walls are connected by top and bottom walls 11 and 12 respectively, and by end walls 13 and 14, 85 whereby an interior chamber of suitable dimensions is formed. Dividing this interior chamber formed as just described is a longitudinally disposed partition 15 that is spaced from the side walls 10 and extends from top to bottom and the respective end walls so that the chamber or interior of the casing is divided into two similar hollow headers 16 and 17, the former being the primary header and communicates with a 90 steam pipe 18 through a bored embossment 19 extending above the top wall 11. Adjacent

cent its lower end the secondary header 17 is provided with an outlet or aperture into which is screwed a discharge pipe 20 through which the condensation and other fluid may escape or be drawn off whenever desired. Opposite pipe 20 the other wall of the casing is provided with a similar aperture that is usually closed by a plug 21 but which may be readily removed in the event an additional pipe is to be employed. The end wall 13 is provided with additional outlets 22 that are preferably closed by plugs as is seen in Figures 1 and 2 and which may be utilized in the manner hereinafter set forth.

The walls 10 are provided with the plurality of threaded apertures in which bushings 23 and 24 are screwed, which bushings carry the cylinders 25 and 26 respectively. The cylinders have closed outer ends 27 and 28 while their inner ends are open, as are the bushings at their inner ends, so that they communicate with the interiors of the respective primary and secondary headers 16 and 17 inside the casing. Aligning with the axes of the threaded apertures that receive the bushings, the partition 15 is also provided with a plurality of threaded apertures extending through the same. Mounted in each cylinder 25 is a tube or pipe 29 having a belled or flared outer end portion 30 and its inner end is carried by an exteriorly threaded bushing 31 that is screwed substantially half-way into its respective aperture in partition 15 so that the tube or pipe 29 is separated or spaced from the cylinder 25 and preferably free of the latter. A similar tube or pipe 32 is mounted in each of the secondary cylinders 26 and are supported at their inner ends in bushings 33 similar to the aforesaid bushings 31.

The circulation of the tempering fluid, such as steam, is through the pipe 18 into the upper portion of the primary header 16 until said header is filled with the steam which finds egress through the bushings 23 and into the cylinders 25 where it passes to the outer ends of said cylinders, around the flared ends 30 of the inner tubes or pipes 29 and then passes longitudinally through said pipes 29 and through the central partition 15 to the opposite tubes or pipes 32 from which it is discharged around the flared ends of the latter into the space between said pipes and the respective cylinders 26. The tempering fluid or steam now passes back into the casing and into the secondary header 17 from which it is discharged through suitable outlets such as pipe 20 hereinbefore mentioned.

It is obvious the steam or tempering fluid will condense upon the interior walls of the structure and I have provided shallow gutters 34 and 35 upon the walls 10 within the respective primary and secondary headers,

and these gutters are each spaced a slight distance above the inwardly extended ends of the bushings 23 and 24 so that the condensation will be carried beyond the circumference thereof. In the event condensation should drip upon the bushings I have provided the latter with annular grooves 36 and 37 respectively upon their inwardly extended ends so as to permit the condensation to drip free of the ends of the bushings and avoid accumulation thereof within the cylinders and pipes.

In Fig. 4 I have illustrated a practical installation of my heat exchanger or unit in connection with the heating of air for the purpose of warming apartments, rooms or the like. The unit in this installation comprises the casing which I designate as A having lateral cylinders B upon the primary side that are shorter in length than the lateral tubes C upon the secondary side. The unit is preferably installed within a suitable housing that is divided longitudinally by a partition wall D so as to provide a feed passageway E in which the primary side B of the unit is disposed and a discharge passageway F in which the secondary side of the coil is positioned. These passageways communicate through the casing G which may be exhausted by a fan so that the untempered air is drawn in through the passageway E, past and circulated around the primary cylinders B, and then blown into the passageway F, past and circulated around the secondary cylinders C. This arrangement, owing to the fact that the primary cylinders B are hotter than the secondary cylinders C, will rapidly raise the temperature of the air passing through the primary side of the structure and discharge the air past the secondary cylinders C in their heated condition, in other words, the air is what might be termed "pre-heated" prior to circulating past the secondary cylinders.

In Figure 5 I have disclosed the embodiment of my heat exchange unit in a tank or cistern G, so that the circulation of the heating fluid through the primary and secondary cylinders B and C respectively from the casing A will raise the temperature of the water in which the exchange unit is emersed or submerged. This is found useful in dairy-farms for preventing the freezing of water for the herds and it is also desirable in laundries and other establishments where it is necessary or desirable to modify the temperature of the water from the service pipes prior to being used.

In Figure 6 I show the casing A as elongated vertically and disposed within a suitable housing H that is provided with an inlet port J and an outlet port K. The housing is preferably air-tight and watertight so that neither air or water may leak

through the same, and the casing A of the tempering unit is adapted to receive brine or other refrigerating fluid that is circulated through the cylinders B which are arranged in the same manner as in the other installations, that is they are disposed upon each side of the casing to provide a primary and a secondary section of the unit. In this connection the water or air is fed into the housing H and is cooled by circulating around and between the cylinders of the unit and is discharged from the housing at a much lower temperature than that at which it enters the same.

It is obvious that a great many other installations could be illustrated, but I have, for the purpose of simplicity, shown but three typical embodiments. It will also be obvious that changes may be made in the structure of the tempering cylinders and the casing with which they co-operate without materially departing from the principle therein disclosed. I therefore desire it understood that refinements or modifications of my invention are fully contemplated within the scope of the appended claims.

What I claim is:

1. A heat exchange unit comprising a hollow casing, a partition dividing the interior thereof into side-by-side headers, a plurality of cylinders extending laterally from opposite walls of said casing and communicating with the interiors of said respective headers and closed at their outer ends, and a plurality of open tubes within the cylinders and extending through said partition and non-communicating with the interiors of the respective headers, said tubes terminating adjacent the outer ends of said cylinders, whereby fluid admitted to one header is conveyed to the outer end of the adjacent cylinders and is conveyed through the partition to the outer end of an opposite cylinder by the respective tubes and is discharged into the interior of the other header of the casing through the inner end of said opposite cylinder.
2. A heat exchange unit comprising a hollow casing, a partition dividing the interior thereof into side-by-side headers, axially aligning cylinders mounted upon opposite walls of said casing and communicating with the interiors of the respective headers, and a tube extending through said partition into said cylinders and terminating adjacent the outer closed ends thereof, whereby fluid from one header is conveyed through the partition by said tube from and to the outer ends of said cylinders.
3. A heat exchange unit comprising a hollow casing, a central partition dividing the interior thereof into side-by-side headers, said partition and the adjacent opposite walls of said casing provided with aligning apertures, a plurality of tubes mounted in

the apertures of said partition and carried thereby and extending from opposite sides of said partition through the respective apertures in said casing, and a plurality of cylinders having open ends secured to the respective apertures and surrounding said tubes upon the exterior of said casing, whereby fluid from one header is conveyed to the other header through the partition by the medium of said tubes in conjunction with said cylinders.

4. A heat exchange unit comprising a hollow casing having apertures therein, a plurality of cylinders mounted in aligning apertures, a plurality of tubes extending through said casing and providing passageways from the outer ends of opposite cylinders, and a partition intermediate the sides of the casing for supporting all of said tubes and through which the passageways pass, which partition divides the casing into opposite side-by-side headers, the construction and arrangement of the partition, tubes and cylinders being such that fluid from one of said headers passes into an adjacent cylinder and is conveyed from its outer end through said partition to the outer end of an aligning cylinder by means of its respective tube and is discharged into the other header through the inner end of said aligning cylinder.

5. In a heat exchange unit a hollow casing having apertures therein, a plurality of cylindrical elements mounted in said apertures and extending externally of said casing, and means upon the interior surface of the walls of said casing for preventing condensation from entering said apertures and cylindrical elements.

6. In a heat exchange unit a hollow casing having oppositely arranged apertures therein, a plurality of cylinders mounted in opposite apertures and extending exteriorly of said casing, gutters formed upon the interior surface of the walls of said casing about each aperture whereby condensation is prevented from entering said apertures and cylinders, and tubes supported within said casing and projecting into said cylinders.

7. A heat exchange unit comprising a hollow casing having apertures therein, cylinders extending from said apertures, a plurality of tubes extending through said casing and providing passageways from the outer ends of said cylinders, said tubes having their outer ends outwardly flared whereby to restrict the passageways formed between said tubes and cylinders and to prevent condensation from entering said tubes, and common means supporting said tubes through which means passageways extend and which divide said casing into oppositely arranged side-by-side headers.

8. A heat exchange unit comprising a

suitably apertured casing, a plurality of cylinders mounted in opposite apertures, a plurality of tubes extending through said casing and into opposite cylinders to provide passageways from opposite outer ends thereof, means for supporting said tubes within said casing, and a feed pipe leading into said casing, the capacity thereof being equal to the combined capacities of all of said tubes.

10

Signed at Chicago, county of Cook and State of Illinois, this 28th day of July, 1923.

JOHN EDWARD ERCANBRACK.
